UNITED STATES PATENT OFFICE

148,669

DESIGN FOR A TRAFFIC SIGNAL

Robert O. Ferguson, Bristol, Tenn., assignor of
one-half to Bristol Steel & Iron Works, Inc.,
Bristol, Va., a corporation of Virginia

Application November 20, 1947, Serial No. 142,693

Term of patent 14 years

(Cl. D72—1)

To all whom it may concern:

Be it known that I, Robert O. Ferguson, a citizen of the United States and a resident of Bristol, in the county of Sullivan and State of Tennessee, have invented a new, original, and ornamental Design for Traffic Signals, of which the following is a specification, reference being had to the accompanying drawing, forming part thereof.

This application is a continuation-in-part of application Serial No. D. 118,338, filed March 8, 1945 (now abandoned).

In the drawing, the figure is a perspective view of a traffic signal showing my new design.

The dominant features of the design reside in the portions shown in full lines, and in particular, in the front face of the signal design shown,

including the hooded bull's-eyes located as shown in the several areas, the said bull's-eyes having arrows as shown in the drawing and the complementary pairs of right-angled lines.

I claim:

The ornamental design for a traffic signal, as shown and described.

ROBERT O. FERGUSON.
